UNITED STATES PATENT OFFICE.

GEORGE F. NICHOLS, OF WOODSBOROUGH, MARYLAND.

DESIGN FOR A WINDOW-FASTENER.

SPECIFICATION forming part of Design No. 33,076, dated August 14, 1900.

Application filed July 18, 1900. Serial No. 24,108. Term of patent 7 years.

To all whom it may concern:

Be it known that I, GEORGE F. NICHOLS, a citizen of the United States, residing at Woodsborough, in the county of Frederick and State of Maryland, have invented and produced a certain new and original Design for Window-Fasteners; and I do declare the following to be a full, clear, and exact description of the invention, such as will enable others skilled in the art to which it appertains to make and use the same.

The invention relates to a new and original design for window-fasteners; and it consists of a design of the shape and configuration shown in the accompanying drawings, in which—

Figure 1 is a side elevation, and Fig. 2 is an edge view.

The leading feature of the device comprises

a flat plate 1, approximately of rectangular formation and having its corners 2 and 3 rounded and its corner 4 provided with an upwardly-projecting tongue 5, having a straight edge 6 and a rounded edge 7, the corner 8 being provided with a downwardly-projecting tongue 9, above which and projecting from the edge 10 of the plate is a rectangular tongue 11.

What I claim is—

The design for a window-fastener, as herein shown and described.

In testimony whereof I have hereunto set my hand in presence of two subscribing witnesses.

GEORGE F. NICHOLS.

Witnesses:

J. Q. LOUGH,

J. V. SILANCE.
